COUNTERBALANCED EXPANSION ROOF

Philip S. Graver, Chicago, Ill., assignor to Graver Tank & Mfg. Co., Inc., East Chicago, Ind., a corporation of Delaware

Application February 7, 1944, Serial No. 521,334

7 Claims. (Cl. 48—176)

1

The invention relates to storage tanks having movable roofs and has reference more particularly to improved counter-balancing means for such movable roofs.

The Graver Patent 2,277,398 granted March 24, 1942, discloses a storage tank for volatile liquids having a roof capable of vertical movement to vary the vapor space within the tank. Since the roof of the storage tank, as shown in said patent, will operate at pressures higher than the maximum safety pressure for cone roofs of tanks connected to it, it is desirable to reduce the operating pressure on said movable roof. Accordingly, an object of the present invention is to provide improved counter-balancing means for reducing the operating pressure on expansion roofs which may be located either exteriorly or interiorly of the tank with the individual weights spaced circumferentially of the same.

A further object is to provide improved counter-balancing means for expansion roofs wherein the counterweights will have movement in a vertical direction which will be twice the distance travelled by the roof, but wherein the said counterweights as a result will be only one-half the weight that would be otherwise required.

A further and more specific object is to provide counter-balancing means for an expansion roof including an arrangement of double sheaves, cables and weights for reducing by half the required weight of the latter with a corresponding reduction in size of the cable and sheaves but wherein said weights will move twice the distance travelled by the expansion roof.

With these and other objects in view the invention may consist of certain novel features of construction and operation as will be more fully described and particularly pointed out in the specification, drawings and claims appended hereto.

In the drawings which illustrate an embodiment of the invention and wherein like reference characters are used to designate like parts—

Figure 1 is an elevational view of an expansion tank embodying the improved counter-balancing means of the invention whereby the roof may be caused to operate at relatively low pressures;

Figure 2 is a fragmentary vertical sectional view illustrating the arrangement of double sheaves, cable and counterweight comprising the invention for counter-balancing an expansion roof; and

Figure 3 is an elevational view of the counter-balancing means shown in Figure 2 illustrating

2

the manner of attaching the sheaves and cable to the tank and roof.

Referring to the drawings, the invention is illustrated as applied to an expansion roof tank having a cylindrical wall 10, a bottom 11 which may rest directly on the earth or other suitable support, and a movable roof designated in its entirety by numeral 12. The cylindrical wall 10 and bottom 11 provide an open top tank which is closed by the movable roof to retain gases or liquids within the structure. The movable roof is of the bell holder type and accordingly the cylindrical wall 10 of the tank is provided with a launder 13 including a base or bottom member 14 formed by the angle 14 suitably secured as by welding to the cylindrical wall of the tank. The launder is located exteriorly of the tank adjacent the upper portion thereof and the vertical wall 15 of the launder is reinforced by the angle member 16 suitably secured as by welding to the top edge of the wall 15 and located exteriorly of the same. The top edge of the cylindrical wall 10 is likewise reinforced by the angle member 17 having location within the tank and extending circumferentially thereof.

The movable roof essentially consists of a center portion 18 covering the entire area of the open top tank structure. Said center portion 18 may have the general shape of a flattened cone, as best shown in Figure 1. A peripheral portion 20 is welded to the circumference of the center portion 18, the same extending substantially horizontally, as shown in Figure 2, and projecting beyond the launder and the angle 16 for reinforcing and strengthening the outer wall of the launder. The roof is completed by the angle 21 located at the junction of the center portion 18 with the peripheral portion 20. It will be understood that the angle 21 extends completely around the roof on the underside of the same and that said angle provides the supporting element for the depending skirt or dip ring 22 having location within the launder 13. The dip ring functions to seal the interior of the tank since the launder contains liquid and at the same time permits vertical movement of the roof to take place.

A depending rain shed skirt 23 is suitably supported from the outer edge of the peripheral portion 20. The rain shed skirt has a length almost equal to that of the launder 13 and for the purposes of the invention the said rain shed skirt is suitably reinforced at intervals by the vertically extending structural members 24, as shown in Figure 3. The upper corner angle 25 functions as a securing element for joining the rain shed

skirt to the roof and the angle 26 fixed to the lower edge of said skirt 23 and extending outwardly of the same strengthens the lower edge. At intervals around the circumference of the rain shed skirt at those places where a counterweight structure is to be located, said rain shed skirt is provided with a depending bracket member 27, the same depending from and being suitably secured to angle 26.

Upward movement of the expansion roof 12 will increase the vapor space within the tank, which action is necessary to retain the volatile vapors produced during the heat of the day. The dotted line position of the roof shown in Figure 1 represents the fully expanded position of the same. As a result of the cooler night temperatures the vapors are condensed and the roof accordingly returns to initial position. The volatile fractions of the liquid stored in the tank will thus be conserved and substantially the same procedure takes place upon filling of expansion roof storage tanks since the filling operation increases the production of vapors which are accommodated by upward movement of the roof.

Unless counter-balancing means are employed the vapor pressure necessary to cause upward movement of the expansion roof 12 is determined primarily by the weight of the roof including the weight of any stabilizing means having fixed relation therewith and which move with the roof. However, by counter-balancing the dead weight of such a roof it is possible to secure operation at much lower pressures. In actual practice it is desirable that tanks equipped with expansion roofs operate on less than one ounce per square inch pressure. If such operation can be secured the expansion tank can be used to store the vapors from a number of conventional fixed roof tanks.

The counter-balancing means of the invention comprises counterweights which act on the roof through the depending rain shed skirt. Thus the counterweights are located exteriorly of the tank. An arrangement of double sheaves is employed, with the result that the counterweights are reduced in weight by half but are required to travel twice the distance travelled by the movable roof for each movement thereof.

The upper sheave 30 is suitably supported by means of the hanger 31 which is pivoted at 32 to the bracket 33. The bracket 33 is part of the reinforcing means for the launder since said bracket is suitably secured to angle 16 as by welding and is likewise welded along its inside edge to wall 15 of the launder. The lower sheave 34 is likewise supported by hanger 35 pivoted at 36 to bracket 37 projecting inwardly from the lower edge of the depending bracket member 27. It will be observed that whereas sheave 30 depends downwardly, the sheave 34 extends upwardly. The cable 38 therefore passes over sheave 30 and under sheave 34. One end of the cable is fixed to the tank, more particularly at the upper edge of the launder, by means of a suitable connection. Said connection may take the form of a bracket 40 secured to the angle 16 and a clevis 41 for joining the end of the cable to said bracket in a pivotal manner. The opposite end of the cable is suitably fixed to the counterweight 42 by means of the eye bolt 43.

During operation of the counter-balancing apparatus of the invention the counterweights 42 will move vertically and since said weights are suspended from sheaves 30 relatively close to the cylindrical wall 10 of the tank, roller means are provided to maintain each weight in proper

spaced relation and facilitate movement of the same. As clearly shown in Figures 2 and 3, each counterweight 42 carries a pair of rollers 44 disposed on the respective sides of the same. Any suitable form of journalling and supporting means, such as the brackets 45, may be employed, projecting from the respective sides of the counterweight. The double arrangement of sheaves makes it possible to reduce the weight of the counterweights 42 by approximately one-half that which would otherwise be required for enabling the expansion roof to operate at a predetermined pressure. The sheave 34 and counterweight 42 constitute the movable elements of each arrangement. When the roof moves in an upward direction for expansion purposes, for example, each sheave 34 will also move in an upward direction, with the result that the counterweights will travel downwardly and the degree of movement of each counterweight will be twice the travel of sheave 34. With the reduction in the weight of the counter-balancing means a reduction is also secured in the size of the sheaves and cable.

What is claimed is:

1. In a tank having an expansion roof with sealing means between the roof and the tank shell, a rain shed skirt depending from the periphery of the roof and encircling the tank shell adjacent the upper portion of the tank, a plurality of upper sheaves supported in spaced relation around the upper edge of the tank shell, lower sheaves secured to the lower edge of the rain shed skirt in spaced relation corresponding to that of the first mentioned sheaves, whereby certain upper and lower sheaves are vertically aligned to form pairs, cables anchored at one end to the upper edge of the tank shell and each extending downwardly to pass under a lower sheave and then upwardly to pass over an upper sheave, and a counterweight secured to the opposite depending end of each cable.
2. In a tank having an expansion roof with sealing means between the roof and the tank shell, a rain shed skirt depending from the periphery of the roof and encircling the tank shell adjacent the upper portion of the tank, and counter-balancing means for said roof including weights, cable means for supporting each weight from the upper edge of the tank shell, and sheaves secured in spaced relation around the upper edge of the tank shell and the lower edge of the rain shed skirt respectively, each said cable means passing under a sheave secured to the skirt and passing over a sheave secured to the tank shell, whereby said weights have movement in a vertical direction which is twice the distance travelled by the expansion roof.
3. In a storage container for gas or liquid, an open top tank arranged to provide a body of sealing liquid, an expansion roof movable with respect thereto to vary the vapor space within the tank, said roof having a depending peripheral skirt located within the sealing liquid so as to confine the gaseous medium within the tank, a rain shed skirt depending from the periphery of the roof and encircling the tank adjacent the upper portion, a plurality of upper sheaves supported in spaced relation around the upper edge of the tank, brackets depending from the lower edge of the rain shed skirt in spaced relation substantially corresponding to that of said sheaves, a lower sheave secured to each bracket, cables anchored at one end to the upper edge of the tank and each extending downwardly to pass under

4. In a storage container for gas or liquid, an open top tank arranged to provide a body of sealing liquid, an expansion roof movable with respect thereto to vary the vapor space within the tank, said roof having a depending peripheral skirt located within the sealing liquid so as to confine the gaseous medium within the tank, a rain shed skirt depending from the periphery of the roof and encircling the tank adjacent the upper portion, a plurality of upper sheaves supported in spaced relation around the upper edge of the tank, brackets depending from the lower edge of the rain shed skirt in spaced relation substantially corresponding to that of said sheaves, a lower sheave secured to each bracket, cables anchored at one end to the upper edge of the tank and each extending downwardly to pass under

a lower sheave and then upwardly to pass over an upper sheave and depend therefrom, and a counterweight secured to said opposite depending end of each cable.

4. In a storage container for gas or liquid, an open top tank arranged to provide a body of sealing liquid, an expansion roof movable with respect thereto to vary the vapor space within the tank, said roof having a depending peripheral skirt located within the sealing liquid so as to confine the gaseous medium within the tank, a rain shed skirt depending from the periphery of the roof and encircling the tank adjacent the upper portion, and counter-balancing means for the roof including a plurality of weights located in spaced relation around the exterior of the tank, cable means for suspending each weight from the upper edge of the tank, and sheaves secured in spaced relation around the upper edge of the tank and around the lower edge of the rain shed skirt respectively, each said cable means passing under a sheave secured to the skirt and passing over a sheave secured to the tank, whereby said weights have movement in a vertical direction which is twice the distance travelled by the expansion roof.

5. In a storage container for gas or liquid, an open top tank arranged to provide a body of sealing liquid, an expansion roof movable with respect thereto to vary the vapor space within the tank, said roof having a depending peripheral skirt located within the sealing liquid so as to confine the gaseous medium within the tank, a rain shed skirt depending from the periphery of the roof and encircling the tank adjacent the upper portion, and counter-balancing means for said roof including a plurality of weights located in spaced relation around the exterior of the tank, cable means for suspending each weight

from the upper edge of the tank, and upper and lower sheaves arranged in pairs around the tank, the upper sheave of each pair being secured to the tank and the lower sheave being secured to a bracket depending from the rain shed skirt, and each said cable means intermediate its ends passing under the lower sheave of the pair associated therewith and over the upper sheave of said pair, whereby said weights have movement in a vertical direction which is twice the distance travelled by the expansion roof.

5 6. In a tank having an expansion roof with sealing means between the roof and the tank shell, a rain shed skirt depending from the periphery of the roof to form a weather hood, upper sheaves pivotally suspended from the upper edge of the tank shell in spaced relation, lower sheaves pivotally secured to the lower edge of the rain shed skirt and correspondingly spaced so that the sheaves form substantially vertically aligned pairs, a cable for each pair, each cable having one end fixed to the tank shell and depending downwardly to pass under a lower sheave and upwardly to pass over an upper sheave and depend therefrom, and a counterweight secured to the depending end of each cable.

10 7. In a tank having a stationary shell member and a vertically movable roof member, pairs of superposed sheaves on said members, the sheaves on said shell member being located above the sheaves on said roof member, and elongated, flexible means extending over the upper sheave of each pair and under the lower sheave of each pair, and having one end secured to said shell member, and a counterweight for said roof member secured to the other end of each of said elongated, flexible means.

PHILIP S. GRAVER.
